UNITED STATES PATENT OFFICE.

BEATRICE MABIE, OF NEW YORK, N. Y.

MASSAGE DEVICE.

Application filed July 2, 1925. Serial No. 41,007.

This invention relates to improvements in massage devices, and more particularly to facial massage instruments of the hand-operated percussion type.

5 One of the objects of my improvement is to provide an instrument so designed that it can be made inexpensively of a single piece of moulded soft rubber with a flexible metal re-enforcement embedded therein.

10 Another object of the invention is to provide an instrument that can be conveniently and comfortably handled, and easily manipulated.

15 A further object is to provide an instrument that is highly flexible in the direction of its percussive action so that beating or patting of the surfaces to be treated may be obtained with minimum effort.

20 These and other objects are attained by means of the construction shown and described herein, it being understood that modifications in the details thereof may be made without departing from the scope of the invention.

25 In the accompanying drawings illustrating a preferred embodiment of the invention:

Figure 1 is a plan view of the instrument;

Fig. 2 is a vertical section through the median line of the instrument in a plane at a 30 right angle to Fig. 1; and,

Fig. 3 is a horizontal section taken on the line 3—3 of Fig. 1.

Referring now to the drawings, 1 indicates the improved instrument which is made of a 35 single piece of soft vulcanized rubber or other suitable material so moulded or formed as to provide a disk-shaped percussion portion 2 at the upper end and a tapered handle portion 3 at the lower end.

A thin flexible metal strip 4 is embedded 40 in the rubber and extends substantially throughout the length of the instrument. The metal strip is entirely concealed and is protected against corrosion by the rubber covering. The strip 4 is disposed with its 45 faces substantially parallel to the faces of the percussion member 2. This arrangement provides a construction that has the desired flexibility in the direction of percussion but is relatively stiff in other directions. 50

The device is operated by grasping the handle and then with a slight motion of the wrist imparting a vibratory motion which causes the percussion disk to deliver a series of light blows on the surfaces to be massaged. 55

What I claim and desire to secure by Letters Patent is:

A massage instrument composed of an integral continuous body of soft rubber having 60 a disk shaped percussion portion at one end thereof and having the remainder of the body shaped to form a handle, and a reinforcing strip of resilient metal and of substantially uniform thickness throughout embedded 65 in the body and centrally of the thickness of the body and having its side faces disposed parallel to the side faces of the body, the strip extending substantially throughout the length of the body and diametrically across the disk shaped percussion portion, the opposed side faces of the handle tapering downwardly and outwardly to provide 70 an enlarged hand grip.

BEATRICE MABIE.
